*Primary Examiner—Jeffrey Asch**Assistant Examiner—Stacia Sinuik**Attorney, Agent, or Firm—Brooks & Kushman P.C.***[57] CLAIM**

The ornamental design for a bicycle wheel, as shown and described.

DESCRIPTION

FIG. 1 is a side perspective view of a bicycle wheel showing the new design;

FIG. 2 is a side view thereof;

FIG. 3 is a rear view thereof; and,

FIG. 4 is a front view thereof.

The broken line showing of the tire and of the bolt in the central hub area is for illustrative purposes only and forms no part of the claimed design.
